J. DE BEER.
KEEL SUPPORT WITH CLAMPS FOR LIFEBOATS.
APPLICATION FILED AUG. 2, 1918.

Patented Jan. 4, 1921.

Fig. 1.

UNITED STATES PATENT OFFICE.

JACOB DE BEER, OF ROTTERDAM, NETHERLANDS.

KEEL-SUPPORT WITH CLAMPS FOR LIFEBOATS.

1,364,730.

Specification of Letters Patent.

Patented Jan. 4, 1921.

Application filed August 2, 1918. Serial No. 248,057.

To all whom it may concern:

Be it known that I, JACOB DE BEER, gentleman, a subject of the Queen of the Netherlands, residing at Rotterdam, in the Province of South Holland, in the Kingdom of the Netherlands, have invented certain new and useful Improvements in Keel-Supports with Clamps for Lifeboats, of which the following is a specification.

10 This invention relates to a keel support with clamps for life boats and has for its principal object to construct a keel support with clamps in such a manner that a boat may be quickly freed from the support and 15 the clamps by a single manipulation. The invention has for a further object to construct the clamps in such a way that after one boat has been released and lowered another boat may be easily placed upon the 20 support. In accordance with the invention, the first object is obtained by placing the keel support further inboard of the ship than the davits and mounting the keel support in such a way in a framework fixed to the deck 25 that it may turn outboard of the ship by its own weight. The support comprises a bar extending substantially lengthwise of the ship, pivoted for rotary movement in the framework, and provided with arms or 30 clamps which extend outboard and also provided with a corresponding number of arms extending inboard, together with suitable locking devices to secure the bar against rotary movement and means for quickly releasing the locking devices.

As the keel support, which is mounted for 35 rocking movement in the deck framework, is placed farther inboard of the ship than the davits, the boat will also be located farther inboard of the ship than the davits when it rests upon the keel support so that 40 when the keel support is released and tilts under the influence of its own weight the boat suspended from the davits by the ropes will swing sidewise until it hangs directly 45 between the davits. The boat may be brought clear of the keel support and the clamps in a very simple manner. In order, after the lowering of a boat, to place another 50 boat upon the keel support this latter boat must, where the ordinary construction of clamps is employed, be lifted or hoisted over the clamps. This is difficult to do. According to the present invention, this difficulty is 55 avoided by hinging to the framework opposite to the clamps on the keel support fur-

ther clamps which may be turned over sideways.

The invention will be described with reference to the accompanying drawings, in 60 which:

Figure 1 is a plan view of a keel support with clamps embodying the invention.

Fig. 2 is an end view showing in full lines a boat resting upon the keel support, in 65 which position it is secured and also showing in dotted lines the positions assumed by the boat and by the keel support after the keel support has rocked on its bearings to permit the boat to hang directly between the 70 davits.

Figs. 3 and 4 are detail views showing connection between the shafts of the releasing levers for the keel support and for the lashings, and

75 Figs. 5 and 6 are, respectively, an end view and an edge view of one end of the deck framework showing the mounting of one of the auxiliary clamps or chocks.

The keel support is hinged or pivoted for 80 rocking movement in deck framework 1 and 3, as shown in Fig. 2, where the axis of rotation is indicated by the numeral 4. The keel support comprises a supporting bar 5 which is provided intermediate its ends with 85 an upright supporting plate 6 and also provided adjacent its opposite ends with corresponding supporting plates 7 and 8. The bar 5 also carries clamps 9 and 10 associated with the plates 7 and 8, which clamps extend 90 from the outboard side of the bar 5. Arms 11 and 12 are also secured to the supporting bar 5 adjacent its opposite ends and extend in the opposite direction from the clamps 9 and 10. The plates 6, 7 and 8 and clamps 9 95 and 10 are preferably so constructed that they over-balance the arms 11 and 12 so that the keel support tends to assume the position shown in dotted lines in Fig. 2.

Approximately under the center of the 100 keel support and extending at a right angle thereto is a sleeve 13 shown as being tubular in form and mounted in bearings 15 and 16 fixed to the deck. The inner ends of rods 17 and 18, which are arranged substantially 105 parallel to the bar 5, are connected at the points 19 and 20, respectively, to crank arms carried by a connecting piece 21 fixed to the sleeve 13. The opposite ends of the rods 17 and 18 are hingedly connected to bolts 110 24 and 25 which move in and are supported by brackets 22 and 23. The bolts 24 and 25

also pass through the deck framework 1 and 3, respectively. In Fig. 1 these bolts are shown as protruding through the framework 1 and 3 and thrust over the extremities 5 of the arms 11 and 12 of the keel support so as to secure the keel support in position to support a boat, as shown in full lines in Fig. 2. In order to actuate the bolt rods to release the keel support, the sleeve 13 must 10 be rocked, and for this purpose, it is provided with a hand lever 26 which, when the bolts are thrust out over the arms 11 and 12, is turned to the right in Fig. 1 and rests upon a support 27. A second lever 28 is se- 15 cured to a rock shaft 13^a extending through the tubular sleeve 13 and a bearing 14 and which, through suitable crank arms secured thereto, may actuate rods 29, 30, 31 and 32, and bolts 33, 34, 35 and 36 connected, re- 20 spectively to said rods which are adapted to slide through fixed bearings 33', 34', 35' and 36'. The bolts 33, 34, 35 and 36 are adapted to engage links at the opposite ends of the lashing chains 45, so that, when the hand 25 lever 28 connected to shaft 13^a is moved to the left (Fig. 1), the lashing ropes are released. The levers 26 and 28 are connected in such a way that they may be operated as one system when a boat is lowered so that 30 the boat will be freed both from the keel support and from its lashings. This connection may consist of a pin *a* carried by the rock shaft 13^a and extending through an opening *b* in the sleeve 13, as shown in 35 Figs. 3 and 4. By removing the pin *a* the rock shaft 13^a may be restored to its locking position in advance of the sleeve 13. The rods 29 and 30 may also be provided with extensions 37 and 38 which serve to secure 40 and release a braking mechanism for the lowering of the boats, such as shown in my co-pending application Serial No. 248,058, filed Aug. 2, 1918. When the lever 26 is moved to the left in Fig. 1 the bolts 24 and 45 25 are, through the connections explained above, withdrawn from the arms 11 and 12 and the keel support rocks by its own weight to the left in Fig. 2 into the position shown in dotted lines. The keel 42 of the boat 43 is then no longer supported so that when the 50 bolts 33, 34, 35 and 36 are withdrawn from the lashings, the boat will swing to the left and then hang directly between the davits. These releasing operations may occur simul- 55 taneously by operating lever 28 which through pin *a* will actuate lever 26 and the bolts 24, 25. The boat, in addition to being supported by the keel support, clamps and supporting plates, as described above, is 60 also supported by further clamps or chocks 39 and 40, shown in Fig. 2, to the right of the keel support and also illustrated in detail in Figs. 5 and 6. The clamps 39 and 40 are, respectively, hinged, as at 41, to the op- 65 posite ends 1 and 3 of the deck framework

so that they may be turned down inwardly, as shown in Fig. 6, to facilitate the placing of another boat upon the keel support. These further clamps or chocks may be secured in upright position by suitable bolts 70 51 carried by the clamps 39 and 40 and engaging the ends 1 and 3 of the deck framework.

After one boat has been launched and it is desired to place another boat on the keel 75 support before releasing the same, the hinged clamps or chocks are turned down so that the boat may be slid on the frame supports 1 and 3 into the position shown in Fig. 2 where it may be secured to the cables 80 44 attached to the davits before releasing the same. If it is desired to secure the boat on the keel rest, the chocks 39 and 40 are rotated about their hinged connections until they assume the upright positions shown in 85 Fig. 2 and engage one side of the boat. The bar 5 is then rotated until the clamping arms 9 and 10 engage the opposite side of the boat, the pin *a* is withdrawn to permit the rock shaft 13^a and sleeve 13 to be operated 90 independently of one another, and the lever arm 26 is actuated to the right in order to lock said clamps in this position by forcing the bolts 24 and 25 over the depending arms 11 and 12. The lashings 45 are then applied 95 over the top of the boat and the handle 28 is turned to the right and projects the bolts 33, 34, 35 and 36 outwardly beyond the end supports 1 and 3 and the bearings 35', 36' to engage the end links of the lashings, thus 100 fastening the boat in the position shown in Fig. 2 from which it may be readily released as above described to assume the position shown in dotted lines in that figure. It will be obvious that by leaving the pin *a* in place 105 the levers 26 and 28 may be actuated together to simultaneously project the bolts which secure the keel supports and the lashings. Other modifications and re-arrange- 110 ments of parts will occur to those skilled in the art to which this invention appertains and I desire to include all such modifications within the spirit of my invention if within the scope of the appended claims.

What I claim is:

1. In mechanism of the class specified forming a boat keel support, frames for se- 115 curement to a boat deck, davits and lashings in coöperative positions to the frames, chocks hinged to the frames and adapted to be locked in fixed upright positions, a shaft mounted below and in the center of the mechanism and having a sleeve thereon of less length than said shaft, levers respec- 120 tively secured to the shaft and sleeve, a sup- porting bar having plates extending upwardly therefrom and pivoted clamps for engagement with the boat keel and comprising upper and lower angularly projecting arms, and rods movably connected at their 125 130

inner ends to said shaft and sleeve and having slide bolts attached to their outer ends to lock the several parts against movement.

2. In mechanism of the class described forming a boat keel support, frames secured to the deck of a vessel, a rotatable shaft, a lever connected to said shaft, a supporting bar having plates extending upwardly therefrom and pivoted clamps for engaging the keel and one side of the boat, said clamps having angularly projecting arms normally tending to assume an inoperative position and means operated by said lever for locking said clamps in operative position.
- 10 3. In mechanism of the class described forming a boat support, frames secured to the deck of a vessel, a rotatable shaft journaled in bearings mounted on the deck of the vessel, a sleeve rotatably mounted on said shaft, levers connected respectively to said shaft and sleeve, a supporting bar having plates extending upwardly therefrom and pivoted clamps for engaging the keel and one side of the boat, said clamps having angularly projecting arms, differing in weight whereby said arms normally tend to assume an inoperative position, means operated by
- 15
- 20
- 25

the lever connected to said sleeve for securing and releasing said clamps and mechanism actuated by the lever connected to said shaft to secure and release lashings about the boat.

4. Mechanism of the class described as specified in claim 3 and a connection between the sleeve and shaft whereby said levers may be actuated simultaneously or independently.

5. In mechanism of the class described forming a boat support, davits mounted on the deck of a vessel, frames secured to the deck of the vessel at the side of and inboards with respect to said davits, means for supporting the boat on said frames having normally a tendency to assume an inoperative position, a locking device for holding said means in operative position, lashing for holding the boat on said frames, mechanism for fastening said lashings and means for releasing said locking device and mechanism whereby said boat may automatically swing to a vertical position between said davits.

In testimony whereof I have hereunto set my hand.

JACOB DE BEER.
